HENRY M. BEECHER, OF PLANTSVILLE, CONNECTICUT, ASSIGNOR TO H. D. SMITH AND COMPANY, OF SAME PLACE.

Letters Patent No. 79,891, dated July 14, 1868.

IMPROVEMENT IN THILL-COUPING.

The Schedule referred to in these Letters Patent and making part of the same.

TO ALL PERSONS TO WHOM THESE PRESENTS MAY COME:

Be it known that I, HENRY M. BEECHER, of Plantsville, in the county of Hartford, and State of Connecticut, have invented a new and useful Improvement in Carriage-Shaft Couplings; and do hereby declare the same to be fully described in the following specification, and represented in the accompanying drawings, of which—

Figure 1 is a side elevation, and

Figure 2 a front end view of a shaft-coupling provided with my improvement, which consists in providing its hinge-connection at its base with lips or projections, to extend laterally from it, and increase the bearing-surface of the base, and receive bolts or screws, to go into the part of the carriage on which the base is to rest.

In the drawings, the hinge-connection is shown at A, as connecting the two parts B C of the coupling, they being in the form which they have as the coupling is made for sale to carriage-makers.

The hinge-connection, instead of being formed in the ordinary way, I make with the curved lips α α , to extend from it, at its base, in opposite directions. Holes to receive screws may be made obliquely through these projections or lips α α , such screws being to hold the base from rising or being moved laterally on the bar on which it is supported when applied to a carriage.

I claim the improved shaft-connection, as made with the lips α α to its base, and in other respects, substantially as described and represented.

HENRY M. BEECHER.
